UNITED STATES PATENT OFFICE.

WILLIAM T. MORGAN, OF NEW BEDFORD, MASSACHUSETTS, ASSIGNOR TO WHITIN MACHINE WORKS, OF WHITINSVILLE, MASSACHUSETTS, A CORPORATION OF MASSACHUSETTS.

BUNCH-BUILDING MECHANISM FOR SPINNING FRAMES.

Application filed September 20, 1926. Serial No. 136,533.

The present invention relates to spinning and winding machines of that type constructed to wind on the yarn bobbin, first a preliminary winding or "bunch" then a main winding, and the principal object of the invention is to provide a mechanism for controlling the short or "bunch" forming traverse of the yarn and is especially adapted for use on that type of spinning machine disclosed in patent to D. O. Pease, No. 1,054,236, dated February 25, 1913, in which the ring rail is stationary and the traverse of the yarn on the bobbin is effected by the reciprocating movements of the spindle rail. I accomplish my object by making use of an auxiliary cam for the preliminary or bunch winding in combination with the usual main traverse cam and automatic means for changing from the preliminary winding to the main winding.

With this object in view, the invention comprises certain novel constructions, combinations and arrangements of parts as will be hereinafter specified and claimed.

In the drawings:—

Figure 1 is a side elevation of the head end of a spinning frame showing my improved bunch builder mechanism thereon.

Figure 2 is a fragmentary sectional elevation on line 2—2 of Figure 1 showing the builder lever and its relation to the builder actuating cams.

Figure 3 is an enlarged side elevation of the builder mechanism showing in full lines the position of the knock-off mechanism when the bunch is being wound and in dotted lines after the bunch is completed and the main wind is being formed.

Figure 4 is an enlarged view showing the bunch as wound by successive short traverses of the yarn on the bobbin.

Similar numerals of reference designate corresponding parts in the several figures.

In the drawings 10 represents the builder lever swingably mounted on the stud 11 fixed to the machine framing 12. A follower roll 13 rotatable on a stud fixed to the builder lever coacts with the main builder cam 14 whereby an up and down motion is imparted to the spindle rail 15 through its connection by means of the chain 16 with the builder lever and thus effecting the main winding of the yarn on the bobbin. Rotary motion is imparted to the cam 14 by the shaft 17

on which it is fixed, said shaft rotatable in bearings supported on the framing of the machine receives its motion through suitable connections with the power transmitting means (not shown in the drawings) of the machine.

Fixed to the shaft 17 is an auxiliary cam 18 which coacts with a follower roll 19 rotatable in bearings affixed to the upper end of a vertical rod 20 slidably mounted in a stand 21 bolted to the machine frame. At the lower end of the rod 20 a latch 22 is hinged which is adapted to abut against a fixed part of the builder lever 10 preferably against the lug 23 formed on the hanger 24 securely fastened to the builder lever.

Preparatory to doffing the machine the operative depresses, with his foot, the builder lever 10 thus disengaging the follower roll 13 from the action of the cam 14 and simultaneously with the depression of the builder lever the knock-off lever 25, by a flexible connection with the builder lever, is shifted on its fulcrum 26 from its normal operative position shown in dotted lines in Figure 3 to the position shown in full lines in the same figure. Preferably I connect the knock-off lever to the builder lever by means of the chain 27 passing over the sheave pulley 28 supported in a bracket 29 fixed to a stationary part of the machine, one end 80 of the chain being fastened to a lug 30 on the builder lever and the other end adjustably connected at 31 to the upper arm of the knock-off lever. A knock-off finger 32 is adjustably mounted at one end to the lower arm of the knock-off lever, the other end being adapted to abut against the side of the latch 22.

While the main wind of the yarn on the bobbin is being accomplished through the action of the cam 14 on its follower roll 13 the latch 22 hangs clear of the abutment 23 on the builder lever and the follower roll 19 is out of contact with the auxiliary cam 18. With the depression of the builder lever by the foot of the operative the knock-off finger allows the latch to swing to a perpendicular position abutting the top of the lug 23 and thus pushing follower roll 19 upward into contact with the auxiliary cam 18, which functions to control the traverse of the yarn in forming the "bunch" on the bobbin. An adjusting screw 33 operates in the lower end

of the latch whereby the amount of separation between the contact surfaces of the main builder cam and its follower roll may be regulated.

5 The auxiliary cam 18 is of the compound type with a plurality of throws whereby a corresponding plurality of reciprocations are imparted to the builder lever for each revolution of the cam and the yarn is thereby wound a corresponding number of short traverses on the bobbin into a bunch 34 with a flat crowning surface such as shown in Figure 4.

15 A knock-off cam 35 fixed to the shaft 17 is provided with a working point 36 which contacts with a stud 37 adjustably mounted on the knock-off lever whereby the latter is swung on its fulcrum and in consequence the knock-off finger pushes the latch 22 from its 20 abutting relation with the builder lever thus transferring the movements of the builder lever from the influence of the preliminary winding cam to the main winding cam.

I claim:

25 1. A bunch builder mechanism for spinning frames, in combination, a swinging builder lever, a shaft rotatable in bearings fixedly connected to the frame of the machine, a cam fixed to said shaft for normally operating the builder lever for effecting the main winding of the yarn on the bobbin, a supplementary cam also fixed to said shaft effects the preliminary winding of the yarn on the bobbin, a device slidably mounted in a stationary part of the machine 30 in a coacting engagement between the builder lever and said supplementary cam, and means for disengaging said device from its coacting engagements.

40 2. A bunch builder mechanism for spinning frames, in combination, a swinging builder lever, a shaft rotatable in bearings fixedly connected to the frame of the machine, a cam fixed to said shaft for normally 45 operating the builder lever for effecting the main winding of the yarn on the bobbin, a supplementary cam also fixed to said shaft effects the preliminary winding of the yarn on the bobbin, a device slidably mounted in 50 a stationary part of the machine and movable in and out of engagement with the supplemental cam and builder lever, means for

automatically effecting the disengagement of the device and manually operated means for effecting its re-engagement with the supplemental cam and builder lever.

55 3. A bunch builder mechanism for spinning frames, in combination, a swinging builder lever, a shaft rotatable in bearings fixedly connected to the machine framing, a 60 cam fixed to said shaft normally operating the builder lever effects the main winding of the yarn on the bobbin, a supplementary cam fixed to said shaft for effecting the preliminary winding of the yarn on the bobbin, a member slidably mounted in a stand fixed to the framing of the machine, the upper end of said member adapted to coact with the supplemental cam, a latch hinged to the lower end of said member adapted to 65 abut against a lug in a fixed relation with the builder lever, and means for disengaging said latch from its abutting relation with the builder lever.

70 4. A bunch builder mechanism for spinning frames, in combination, a swinging builder lever, a shaft rotatable in bearings fixed to the machine frame, a cam fixed to said shaft normally operating the builder lever effecting the main winding of the yarn 75 on the bobbin, a supplementary cam fixed to said shaft for effecting the preliminary winding of the yarn on the bobbin, a member slidably mounted in a stand fixed to the framing of the machine, a follower roll attached to the upper end of said member and adapted to coact with the supplemental cam, a latch hinged to the lower end of said member, a lug on the builder lever against which the latch is abuttable, a knock-off lever pivoted to the framing of the machine, a knock-off finger, one end of which is adjustably mounted on the lower part of the knock-off lever and the other end is in an abutting relation with the said latch, a knock-off cam 80 fixed to rotatable shaft coacts with a stud on knock-off lever to disengage said latch, and a flexible connection between knock-off lever and builder lever effects the reengagement of the latch with the builder lever.

85 90 95 100 In testimony whereof, I have signed this specification.

WILLIAM T. MORGAN,
